UNITED STATES PATENT OFFICE.

IMRIE RUDAI AND AUGUST SZARKA, OF VESTABURG, PENNSYLVANIA.

COAL-MINING MACHINE.

1,274,939.

Specification of Letters Patent. Patented Aug. 6, 1918.

Application filed May 6, 1918. Serial No. 232,923.

To all whom it may concern:

Be it known that we, IMRIE RUDAI and AUGUST SZARKA, subjects of the King of Hungary, residing at Vestaburg, in the 5 county of Washington and State of Pennsylvania, have invented new and useful Improvements in Coal-Mining Machines, of which the following is a specification.

Our invention relates to mining machines, 10 and more particularly to apparatus by which such machines may be moved from place to place by means of the motive power for effecting the mining operations.

Our object is to provide improved means 15 for using the mining machine motor instead of hand levers to move the mining machine to and from a truck or to various positions on the mine floor preliminarily to mining operations.

20 Referring to the accompanying drawings, Figure 1 is a plan view of a coal mining machine with our invention embodied therein; Fig. 2, a side elevation of Fig. 1; Fig. 3, an enlarged side view of the gearing shown 25 on Fig. 2; Fig. 4, a horizontal section on the line IV—IV of Fig. 2 with the mining machine carriage and cutter omitted; Fig. 5, an end view of the cable drum; Fig. 6, a fragmentary view, showing the upper part 30 of Fig. 5 enlarged and parts in a different position; Fig. 7, a central vertical section through Fig. 5; Fig. 8, a detail showing a portion of the gearing for connecting the 35 motor to the means for moving the machine; Fig. 9, a section on the line IX—IX, Fig. 6; and Fig. 10, a view of a hook for the drum cable.

On the drawings, 1 represents the shoes, 2 the side bars, and 3 the cross bars of a 40 mining machine frame A. In this frame is the movable cutter frame 4 provided with the endless chain 5 bearing the cutters 6. This chain is driven by the motor 7 which is mounted to travel back and forth upon 45 the machine frame A. The mechanism so far described and that now about to be described for moving the motor, its carriage and the cutter frame back and forth are all old and need not be fully described. 50 The details may be seen in Dierdorff's Patent, No. 684,356, dated October 8, 1901.

8 designates the armature shaft of the motor 7 and drives the spur gear wheel 9 on the shaft 10. This shaft by suitable 55 gearing drives the worm 11 in one direc-

tion, and the motor by suitable gearing drives the worm wheel 12 in the opposite direction. The worms gear with the worm wheels 13 and 14, respectively, which run loose on the shaft 15. The shaft 15 has 60 fixed thereon at its ends the spur pinions 16 and 17 which gear with the respective racks 18 and 19 on the lower faces of the top-plates 20 of the frame. 21 is a clutch on the shaft 15 which may be thrown in opposite 65 ways from its central position by the lever 22 so as to cause the shaft 15 to drive the worm 13 or the worm 14. When the clutch is in the central position it is disconnected from both worm wheels. Thus, when the 70 motor is running, the carriage and cutter frame may be moved forward on the frame A to make a cut in the coal and then backward out of the kerf, or the motor may run idle without operating the cutter carriage. 75

Our invention may be applied to any other type of coal mining machine as the details thereof form no part of the same. In the frame A we mount the spur gear 80 23, which may be moved up into engagement with the gear wheel 9 when the motor carriage is in its rear position, as shown on Figs. 2 and 3. The spur pinion 24 integral with the gear 23 meshes with the gear 25, which meshes with the gear 26, loose on the shaft 27, extending entirely across the frame.

The end of the shaft 27 opposite the one bearing the gear 26 has the pinion 28 fixed 90 thereon and meshing with the gear 29 on the shaft 30, which also has fixed thereon the pinion 31 meshing with the internal gear 32 on the wheel 33 fixed on the shaft 34. The shaft 34 has the rope drum 35 95 loosely mounted thereon and having its inner face provided with peripheral teeth 36, engageable by the radially-slidable toothed segment 37 carried by the outer face of the wheel 33. The segment is slidable in the 100 slot 38 in the wheel 33 and when pushed in radially in the slot, the arc-shaped key or slide 39 guided in a slot between the wheel 33 and the strip 40 thereon is moved between the outer end of the segment and the 105 strip. The key and the strip 40 have a tongue and groove connection 41, as shown on Fig. 9 to prevent the lateral movement of the key. When the key is moved back to allow the segment 37 to be moved out- 110

wardly out of mesh with the teeth 36, its forward end engages in a notch 42 in the adjacent end of the segment to prevent the accidental inward movement of the segment, 5 the key being pushed toward the notch by the spring 43 engaging the other end of the key.

The shaft 27 is provided with the clutch 44 operated by the lever 45 to disconnect 10 the shaft 27 from its driving gear 26 and stop the rotation of the drum 35.

The gears 23 and 24 are mounted fixedly on the shaft 46 provided with the pinions 47 engageable with the racks 48 in one side 15 of the vertical guides 49 between which the pinions 47 are moved up and down and by which the gears 23 and 24 are held from lateral movement. When the shaft 46 is at the bottom of the guides, the gears 9 and 20 23 are disengaged. By applying a wrench to the squared end of the shaft 46 the latter is caused to move up between its guides 49. When the shaft is near its upper position, the slides 50 and 51 are moved beneath the 25 ends of the shaft and wedge them upwardly by an incline 52 on the upper edge and cause the gears 9 and 23 to engage each other. These slides hold the gears in engagement, with the pinions 47 out of mesh with the 30 racks 48. The slides are operated by the lever 53 having its ends pivoted to the slides and its middle to the fixed support 54 on the frame. 55 is a handle for operating the slides.

35 On the rear end of the frame are pivoted the two sheaves 56 and 57. The rear end of the frame carries also the transverse bar 56' which carries the pin 57' extending through the sheave 58 lying between the sheaves 56 40 and 57. Sheaves 59 and 59' connected to bars 60 may be hooked over the frame or other objects. 61 is a rope on the drum 35.

When it is desired to move the entire mining machine on its shoes 1 over the floor 45 of the mine or other surface, the motor carriage is moved to the rear with the gear 9 over the gear 23. The clutch 21 is moved to its central position, and the segment 37 is interlocked with the teeth 36. The rope 61 50 is passed over certain sheaves as shown and its end secured to any convenient stationary object located so as to pull the machine in the desired direction. The gear 23 is moved into mesh with the gear 9 and the clutch 55 44 into engagement with the gear 26, whereupon, the motor 7 having been started, the entire machine will be moved on its shoes.

When the rope is passed over the sheaves 56 and 58, as in Fig. 4, the machine will be 60 moved to the right. The rope may be passed over the sheaves 56 and 57 to move it to the left, and over the sheave 59 to move it forwardly. The rope may be passed over the sheave 59' directly from the drum to 65 move the machine to the right. When it is

desired to wind up the rope on the drum or to pay out the rope, the segment 37 is moved out of engagement with the teeth 36, whereupon the drum can be rotated idly on the shaft 34.

A double-ended hook 62 may have one hook connected to a bar or jack 63, the rope 61 running through the other end as shown on Fig. 10 to cause the machine to be pulled in the desired direction. The hook 62 may 75 be hooked over any convenient object or be used like the sheaves 59 and 59' and their bars 60.

After the machine has been moved into position for cutting coal, the slides 51 are so drawn from under the shaft 46, and the gear 23 drops away from the gear 9, so that the motor carriage may move forwardly without operating the gears for moving the frame.

We claim—

1. In a mining machine, a frame, a rope-drum thereon, a cutter-carriage on the frame, a motor on the carriage for driving the same and the cutter, a gear on the carriage driven by the motor and gearing on the frame for driving the rope-drum, one of the gears of said gearing being movable into mesh with the gear on the carriage.

2. In a mining machine, a frame, a rope-drum thereon, a cutter-carriage on the frame, a motor on the carriage for driving the same and the cutter, a gear on the carriage driven by the motor, gearing on the frame for driving the rope-drum, one of the gears of said gearing being movable into mesh with the gear on the carriage, a shaft to which the movable gear is secured, pinions on the ends of the shaft, guides leading toward the carriage gear and having racks for meshing with the pinions, whereby the shaft may be caused to move in the guides toward the carriage gear, and means for maintaining the said gears in mesh.

3. In a mining machine, a frame, a rope-drum thereon, a cutter-carriage on the frame, a motor on the carriage for driving the same and the cutter, a gear on the carriage driven by the motor, gearing on the frame for driving the rope-drum, one of the gears of said gearing being movable into mesh with the gear on the carriage, and a clutch between the said movable gear and the rope-drum.

4. In a mining machine, a frame, a rope-drum thereon, a cutter-carriage on the frame, a motor on the carriage for driving the same and the cutter, gearing on the frame for driving the rope-drum, and means for connecting the motor to the said gearing, the said gearing on the frame including a wheel having a toothed segment movable into locking engagement with the rope-drum for driving the latter.

5. In a mining machine, a frame, a rope-

drum thereon, a cutter-carriage on the frame, a motor on the carriage for driving the same and the cutter, gearing on the frame for driving the rope-drum, and means for connecting the motor to the said gearing, the said gearing on the frame including a wheel having a toothed segment movable into locking engagement with the rope-drum for driving the latter, in combination with means for holding the segment in such engagement.

6. In a mining machine, a frame, a rope-drum thereon, a cutter-carriage on the frame, a motor on the carriage for driving the same and the cutter, gearing on the frame for driving the rope-drum, and means for connecting the motor to the said gearing, the said gearing on the frame including a wheel having a toothed segment movable into locking engagement with the rope-drum for driving the latter, in combination with a

key movable against the segment to prevent its movement away from the drum.

7. In a mining machine, a frame, a rope-drum thereon, a cutter-carriage on the frame, a motor on the carriage for driving the same and the cutter, gearing on the frame for driving the rope-drum, and means for connecting the motor to the said gearing, the said gearing on the frame including a wheel having a toothed segment movable into locking engagement with the rope-drum for driving the latter, in combination with a key movable against the segment to prevent its movement away from the drum and to prevent its movement toward the drum when disengaged therefrom.

Signed at Pittsburgh, Pa., this 3rd day of May, A. D. 1918.
